(57) **CLAIM**

The ornamental design for a display screen with graphical user interface, as shown and described.

DESCRIPTION

FIG. 1 is a front view of a first embodiment of a display screen with graphical user interface;

FIG. 2 is a perspective view thereof being applied to an exemplary user device;

FIG. 3 is a front view of a second embodiment of a display screen with graphical user interface; and,

FIG. 4 is a perspective view thereof being applied to an exemplary user device.

The ornamental design includes a graphical user interface. The even-length broken lines shown in FIGS. 1 and 2 illustrate portions of the graphical user interface that form no part of the claimed design.

The outermost uneven-length broken lines of FIGS. 1 and 3 illustrate a display screen or portion thereof and form no part of the claimed design.

In FIGS. 2 and 4, the graphical user interface is shown applied to an exemplary user device, which is illustrated in uneven-length broken lines and forms no part of the claimed design.
